(57) **CLAIM**

The ornamental design for a camping lamp, as shown and described.

DESCRIPTION

FIG. 1 is a front, top, and right side perspective view of a camping lamp showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a rear, bottom, and left side perspective view thereof.

The broken lines throughout the drawing figures depict portions of the camping lamp that form no part of the claimed design.
